(57) **CLAIM**

The ornamental design for a trigger sprayer shroud, as shown and described.

DESCRIPTION

FIG. 1 is a perspective view of a trigger sprayer shroud showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another perspective view thereof, shown in a position of use with an exemplary bottle.

The broken lines are shown for the purpose of illustrating both parts of the article as well as environmental subject matter of an exemplary spray bottle. None of the broken lines form part of the claimed design.
